UNITED STATES PATENT OFFICE

ROLAND R. CRUM, OF WHITTIER, CALIFORNIA, ASSIGNOR TO H. C. SMITH MANUFACTURING COMPANY, OF WHITTIER, CALIFORNIA, A CORPORATION OF CALIFORNIA

EXPANSIBLE UNDERREAMER

Application filed October 15, 1928. Serial No. 312,474.

This invention relates to an expandable underreamer having a longitudinally movable cutter arranged to be moved laterally to and from the body to expand and collapse the underreamer. The present invention contemplates the provision of a sloping surface for engagement by a complementary surface on a cutter member to cause the cutter member to be moved laterally on longitudinal movement thereof.

The objects of this invention are to provide an underreamer of the character described having any or all of the following features:—hydraulic means for actuating the cutters; such hydraulic means operated by the pressure of circulation fluid employed in hydraulic drilling; and novel features of construction contributing to simplicity, durability and certainty in operation.

These objects together with other objects and corresponding accomplishments are obtained by means of the embodiment of my invention illustrated in the accompanying drawing, in which:—

Fig. 1 is an elevation of an underreamer; Fig. 2 is a central longitudinal section showing the underreamer parts in collapsed position; Fig. 3 is a central longitudinal section showing the underreamer parts in expanded position; Fig. 4 is a section as seen on the line 4—4 of Fig. 3; and Figs. 5 and 6 are sections as seen on the lines correspondingly numbered in Fig. 1.

Referring more particularly to the drawing, 10 indicates a body having a pin 11 at its upper end for attachment to a drill string and a bit 12 at the lower end for drilling. It will be understood that the bit forms no part of the present invention, and that the body of the underreamer may be constructed for detachably securing drilling tools of various characters thereto. The body is illustrated as formed of two parts secured together by a box and pin connection, the upper part having a circulation passage 13 extending therethrough. The lower portion of the bit has an enlarged cylindric chamber 14 serving as a cylinder for a piston. The circulation passage is extended through the body as indicated by 15 opening through

water courses to flush the bit 12. A relief port 16 communicates with the cylinder chamber. Extending longitudinally of the body are three cavities 17 to accommodate three cutter members. However, the invention is not limited to any particular number of cutter members. The cavities are duplicates of one another as are the cutters disposed therein and it will be sufficient to describe one. The inner wall of a cavity is stepped and intermediate the steps is a ramp 18 sloping upwardly and outwardly. The outer stepped surface serves as a supporting surface for a bearing block on the cutter members later described. A slot 19 extending longitudinally of the body is formed in the step for accommodating a cross pin. Ranging downwardly from the cylinder chamber is an opening 20 for slidably receiving a connecting rod. A pivot pin 21 spans the cavity at its lower end.

Fulcrumed to the body on the pivot pins 21 are lower shaft blocks 22, each having an elongated slot 23 of such width as to provide for a limited lateral play of the block, there being a bearing face 24 on the block to rest against the inner wall of the cavity in expanded position of the cutter. A socket is provided in each block to receive the end of a cutter shaft 25 having cutter rollers 26 journaled thereon. At the upper end of shaft 25 and secured thereto is a shaft block 27 having an opening extending therethrough in which may be disposed a cross pin 28. The opening is enlarged at its outer face to accommodate a nut on the end of the pin, and the reduced portion is enlarged sufficiently to allow a slight play of the pin in the opening. The inner upper face of block 27 is bevelled so as to provide a sloping surface 29 complementary to the ramp 18. A slot is also provided to accommodate a connecting rod joined to the cross pin.

Disposed within the piston chamber 14 and secured thereto in any suitable manner such as by welding or a shrunk fit is a head 30. The head has a tubular extension 31 and slidably mounted thereon is a piston 32. A connecting rod 33 for each cutter is secured to the piston and at the lower end

is attached to a cross pin 28. A number of passages 34 open from the working end of the piston chamber to the cavity for delivering circulation wash to the cavities for flushing the cutters. These passages are of such cross-sectional area that a pressure will be developed in the working space upon delivery of circulation thereto.

The tool is collapsed by moving the cutter members downwardly and with them the piston 32 to the position shown in Fig. 2. In this position the bearing surfaces 29 rest against the ramps 18. In this condition the underreamer is inserted in the casing and lowered. Upon introduction of circulation fluid under pressure and passage of the cutters below and out of the casing, the piston 32 will be moved upwardly carrying the cutter members and causing them to ride outwardly upon their ramps into position with the rear faces of the blocks 27 resting against the outer steps and serving as a support for the upper ends of the cutters.

What I claim is:—

1. In an underreamer, the combination of a body, having a longitudinally extending cavity in its periphery with a stepped inner surface at one end and an outwardly sloping ramp intermediate the steps, a cutter accommodated in said cavity for longitudinal play therein and having a connection to said body so that it may be moved laterally thereon into and out of expanded position, a supporting block secured to said cutter adjacent to said ramp, said block having a supporting surface to engage and coact with the outer step and a sloping bearing surface for engaging said ramp to cause said cutter to be projected upon upward movement thereof into expanded position, a cylinder chamber communicating with a source of fluid pressure, a piston in said cylinder, and a connecting rod for actuating said cutter to move the latter longitudinally upon introduction of fluid under pressure into said chamber so as to cause said block to ride outwardly over said ramp into position with said supporting surface overlapping the outer stepped surface.

2. In an underreamer, the combination of a body having a longitudinally extending cavity in its periphery with a stepped inner surface adjacent one end and an outwardly sloping ramp intermediate the steps, a cutter accommodated in said cavity for longitudinal play therein and having a fulcrum connection to said body so that it may be rocked laterally thereon into and out of expanded position, a block secured to said cutter at the end opposite to said fulcrum and having a supporting surface to engage and coact with the outer step and a sloping bearing surface for engaging said ramp to cause said cutter to be projected upon longitudinal movement thereof into expanded position, a

cylinder chamber communicating with a source of fluid pressure, a piston in said chamber, and a connecting rod for actuating said cutter to move the latter longitudinally upon introduction of fluid under pressure into said chamber so as to cause said block to ride outwardly over said ramp into position with said supporting surface overlapping the outer step surface.

3. In an underreamer, the combination of a body having a longitudinally extending cavity in its periphery with a stepped inner surface at its upper end and an outwardly sloping ramp intermediate the steps, a cutter accommodated in said cavity for longitudinal play therein and having a connection to said body so that it may be moved laterally thereon into and out of expanded position, a block secured to said cutter at its upper end and having a supporting surface to engage and coact with the outer step and a sloping bearing surface for engaging said ramp to cause said cutter to be projected upon upward movement thereof into expanded position, a cylinder chamber communicating with a source of fluid pressure, a piston in said chamber, and a connecting rod for actuating said cutter to move the latter upwardly upon introduction of fluid under pressure into said chamber so as to cause said block to ride outwardly over said ramp into position with said supporting surface overlapping the outer step surface.

4. In an underreamer, the combination of a body having a longitudinally extending cavity in its periphery with a stepped inner surface at its upper end and an outwardly sloping ramp intermediate the steps, a cutter accommodated in said cavity for longitudinal play therein and having a fulcrum connection to said body at its lower end so that it may be rocked laterally thereon into and out of expanded position, a block secured to said cutter at its upper end and having a supporting surface to engage and coact with the outer step and a sloping bearing surface for engaging said ramp to cause said cutter to be projected upon upward movement thereof into expanded position, a cylinder chamber communicating with a source of fluid pressure, a piston in said chamber, and a connecting rod for actuating said cutter to move the latter upwardly upon introduction of fluid under pressure into said chamber so as to cause said block to ride outwardly over said ramp into position with said supporting surface overlapping the outer step surface.

5. In an underreamer, the combination of a body having a longitudinally extending cavity in its periphery with a stepped inner surface at its upper end and an outwardly sloping ramp intermediate the steps, a cutter accommodated in said cavity for longitudinal play therein and having a connection to said body so that said cutter may be

5 moved laterally into and out of expanded position, a block secured to said cutter at its upper end and having a supporting surface to engage and coact with the outer step and a sloping bearing surface for engaging said ramp to cause said cutter to be projected upward upon upward movement thereof into expanded position, a cylinder chamber in said body above said cutter communicating with a source of fluid pressure, a piston in 10 said cylinder, and a connecting rod depending from said piston for actuating said cutter and causing it to be moved upwardly upon introduction of fluid pressure into said chamber so as to cause said block to ride outwardly over said ramp into position with said supporting surface overlapping the outer step surface.

15 6. In an underreamer, the combination of a body having a longitudinally extending cavity in its periphery with a stepped inner surface at its upper end and an outwardly sloping ramp intermediate the steps, a cutter accommodated in said cavity for longitudinal play therein and having a fulcrum connection to said body at its lower end so that said cutter may be rocked laterally into and out of expanded position, a block secured to said cutter at its upper end and having a supporting surface to engage and coact with the outer step and a sloping bearing surface for engaging said ramp to cause said cutter to be projected upon upward movement thereof into expanded position, a cylinder chamber in said body above said cutter communicating with a source of fluid pressure, a piston in 20 said cylinder, and a connecting rod depending from said piston for actuating said cutter and causing it to be moved upwardly upon introduction of fluid pressure into said chamber so as to cause said block to ride outwardly over said ramp into position with said supporting surface overlapping the outer step surface.

25 7. In an underreamer, the combination of a body having a longitudinally extending cavity in its periphery with an outwardly sloping ramp at its upper end, a cutter accommodated in said cavity for longitudinal play therein and having a connection to said body so that it may be moved laterally thereon into and out of expanded position, a block secured to said cutter at its upper end and having a sloping bearing surface for engaging said ramp to cause said cutter to be projected upon upward movement thereof into expanded position, a cylinder chamber in said body communicating with a source of fluid pressure, a piston in said chamber, and a 30 connecting rod for said piston and said cutter to cause the latter to be moved upwardly upon introduction of fluid pressure into said chamber so as to cause said block to ride outwardly over said ramp with said cutter in expanded position.

35 8. In an underreamer, the combination of a body having a longitudinally extending cavity in its periphery with an outwardly sloping ramp at its upper end, a cutter accommodated in said cavity for longitudinal play therein and having a connection to said body so that it may be moved laterally thereon into and out of expanded position, a block secured to said cutter at its upper end and having a sloping bearing surface for engaging said ramp to cause said cutter to be projected upon upward movement thereof into expanded position, a cylinder chamber in said body above said cutter communicating with a source of fluid pressure, a piston in 40 said cylinder, a connecting rod depending from said piston for actuating said cutter and causing it to be moved upwardly upon introduction of fluid pressure into said chamber so as to cause said block to ride outwardly over said ramp into position with said cutter projected.

45 9. In an underreamer, the combination of a body having a longitudinally extending cavity in its periphery with an outwardly sloping ramp at its upper end, a cutter accommodated in said cavity for longitudinal play therein and having a fulcrum connection to said body at its lower end so that it may be rocked laterally thereon into and out of expanded position, a block secured to said cutter at its upper end and having a sloping surface for engaging said ramp to cause said cutter to be projected upon upward movement thereof into expanded position, a cylinder chamber in said body communicating with a source of fluid pressure, a piston in 50 said cylinder, and a connecting rod for said piston and cutter to actuate the latter and cause it to be moved upwardly upon introduction of fluid pressure into said chamber so as to cause said block to ride outwardly over said ramp into position with said cutter expanded.

55 10. In an underreamer, the combination of a body having a longitudinally extending cavity in its periphery with an outwardly sloping ramp at its upper end, a cutter accommodated in said cavity for longitudinal play therein and having a fulcrum connection to said body so that it may be rocked laterally thereon into and out of expanded position, a block secured to said cutter at its upper end and having a sloping bearing surface for engaging said ramp to cause said cutter to be projected upon upward movement thereof into expanded position, a cylinder chamber in said body above said cutter communicating with a source of fluid pressure, a piston in 60 said cylinder chamber, and a connecting rod depending from said piston for actuating said cutter and causing it to be moved upwardly upon introduction of fluid pressure into said chamber so as to cause said block to ride outwardly over said ramp into position with said cutter in expanded position.

- position with said cutter in expanded position.
11. In an underreamer, the combination of a body having a longitudinally extending cavity in its periphery with an outwardly sloping ramp at its upper end, a cutter accommodated in said cavity for longitudinal play therein and having a connection to said body so that it may be moved laterally thereon into and out of expanded position, a block secured to said cutter at its upper end and having a sloping bearing surface for engaging said ramp to cause said cutter to be projected upon upward movement thereof into expanded position, a circulation passage in said body, a piston chamber in said body, a piston in said chamber, a conduit connecting said circulation passage to the cylinder space below said piston, and a connecting rod for said piston and said cutter to actuate the latter and cause it to be moved upwardly upon introduction of circulation pressure into said chamber so as to cause said block to ride outwardly over said ramp into position with said supporting surface overlapping the outer step surface. 70
12. In an underreamer, the combination of a body having a longitudinally extending cavity in its periphery with a stepped inner surface at its upper end and an outwardly sloping ramp intermediate the steps, a cutter accommodated in said cavity for longitudinal play therein and having a fulcrum connection to said body at its lower end so that said cutter may be rocked laterally into and out of expanded position, a block secured to said cutter at its upper end and having a supporting surface to engage and coact with the outer step and a sloping bearing surface for engaging said ramp to cause said cutter to be projected upon upward movement thereof into expanded position, a circulation passage in said body, a piston chamber in said body above said cutter, a piston in said chamber, a conduit connecting said circulation passage to the cylinder chamber space below said piston, and a connecting rod depending from said piston for actuating said cutter and causing it to be moved upwardly upon introduction of fluid pressure to said chamber so as to cause said block to ride outwardly over said ramp into position with said supporting surface overlapping the outer step surface. 80
13. In an underreamer, the combination of a body having a longitudinally extending cavity in its periphery with an outwardly sloping ramp intermediate the steps, a cutter accommodated in said cavity for longitudinal play therein and having a connection to said body so that it may be moved laterally thereon into and out of expanded position, a block secured to said cutter at its upper end and having a sloping bearing surface engaging said ramp to cause said cutter to be projected upon upward movement thereof into expanded position, a circulation passage in said body, a piston chamber in said body located above said cutter, a piston in said chamber, a conduit connecting said circulation passage to the cylinder chamber space below said piston, and a connecting rod depending from said piston for actuating said cutter and causing it to be moved upwardly upon introduction of circulation pressure into said chamber so as to cause said block to ride outwardly over said ramp into position with said cutter expanded. 90
14. In an underreamer, the combination of a body having a longitudinally extending cavity in its periphery with a stepped inner surface at its upper end and an outwardly sloping ramp intermediate the steps, a cutter accommodated in said cavity for longitudinal play therein and having a fulcrum connection to said body at its lower end so that said cutter may be rocked laterally into and out of expanded position, a block secured to said cutter at its upper end and having a supporting surface to engage and coact with the outer step and a sloping bearing surface for engaging said ramp to cause said cutter to be projected upon upward movement thereof into expanded position, a circulation passage in said body, a piston chamber in said body above said cutter, a piston in said chamber, a conduit connecting said circulation passage to the cylinder chamber space below said piston, and a connecting rod depending from said piston for actuating said cutter and causing it to be moved upwardly upon introduction of fluid pressure to said chamber so as to cause said block to ride outwardly over said ramp into position with said supporting surface overlapping the outer step surface. 95
- In witness that I claim the foregoing I have hereunto subscribed my name this 20th day of September, 1928. 100
